FIG. 4.

GLENWOOD EMANUEL NELSON.
ALBERT EDGAR BARKER.

INVENTOR.

BY

Paul C. Chapman
ATTORNEY.

UNITED STATES PATENT OFFICE

GLENWOOD EMANUEL NELSON AND ALBERT EDGAR BARKER, OF GODERICH, ONTARIO,
CANADA

AWNING SAVER

Application filed October 9, 1930. Serial No. 487,460.

This invention relates to awnings and has as its principal object a means for encasing an awning after the same has been rolled up.

A further object is to provide means for raising and lowering an awning, which means will retain the awning in various predetermined positions.

A further object is to provide a means whereby the gable portions of the awning are formed integral with the body portion and may be rolled up flat with the body portion of the awning into a casing.

With the foregoing and other objects in view as will appear as the description proceeds, the invention consists of the novel construction, combination and arrangement of co-operating elements as hereinafter more specifically set forth, claimed and shown in the accompanying drawings forming a part 20 of this application, in which:

Fig. 1 is a front view of the preferred embodiment of my invention, the awning being rolled up within the casing.

Fig. 2 is an end view of the preferred embodiment of my invention, parts being broken away and the awning being in extended position.

Fig. 3 is a sectional view taken on the line 3—3 of Fig. 1.

Fig. 4 is a view of the awning looking up from under, the same being in extended position.

Like numerals of reference designate corresponding parts throughout the different views.

It has been the custom for merchants or other persons to dismantle their awning and store them away during the winter months. This dismantling and storing away of the same necessitated considerable labour and inconvenience. Also while the awning is in use, it is customary to roll it up on its roller during inclement weather, leaving certain portions of the same exposed to rain, sleet, snow or the like, which would damage the awning to a great extent. These disadvantages are overcome by the present invention, as the awning, when rolled up, is completely encased and non-exposed to such weather conditions.

5 is a cylindrical casing supported from the face 6 of a building by means of brackets 7 and 8. 9 is a longitudinal hinged portion of the casing adapted to be swung outwardly as at 9a (Fig. 2) to provide an opening 55 through which the awning 10 may extend. 11 are circular discs which provide the end closure members for the casing. The brackets 7 are each provided at their outer end with a bearing 12, in which the rod 14 is rotatably supported. 15 are lever arms fixedly supported at one end on the rod 14, which arms extend outwardly over the hinged portion 9. 16 are brackets fixedly connected to the hinged portion 9. Connected at one end to 60 the outer ends of the respective lever arms 15 and their opposite end to the respective brackets 16, we provide connecting links 17. 18 are suitable hinges connecting the hinged portion 9 to the casing 5. Referring 65 to Fig. 3, it will be noted that the upper edge of the hinged portion 9 extends under the forward edge of the casing 5 while the lower edge of the hinged portion 9 extends under the lower forward edge of the casing 5. 70 This arrangement of parts eliminates the possibility of rain, sleet, snow or the like gaining access to the interior of the casing.

One end of the rod 14 is provided with a fixedly connected forked head 19. 20 is a gear box in which a worm gear 21 and a worm pinion 22 are disposed in intermeshing relation. 23 is a vertical shaft the lower end of which extends into the shank portion 24 of the worm gear 21 and is held in fixed relation 80 thereto by means of the pin 25 which extends through the slot 26 across the lower end of the shaft 23. The upper end of the shaft 23 is forked as at 27. 28 is a connecting link 85 between the shaft 23 and the rod 14. The ends of this connecting link are universally connected to the respective forked ends of the shaft 23 and the head 19. 29 is a roller 90 within the casing 5 upon which the awning 10 is adapted to be rolled. The roller 29 is supported between the circular discs 11 and one end extends outwardly through the casing as at 29a. 30 is a bevel gear fixedly supported on the extended end 29a. 31 is a worm gear 95 provided with a bore 32, which fits over the 100

shank portion 24 of the worm gear 21. The worm gear 31 is provided with an upwardly extending shank portion 33 into which is fixedly connected a tubular shaft 34. Fixedly connected to the upper end of the tubular shaft 34 is a collar 35. 36 is a bevel gear fixedly connected to the upper end of the collar 35, which bevel gear meshes with the bevel gear 30 on the extended portion 29a of the roller 29. 37 is a worm pinion meshing with the worm gear 31. The worm pinions 22 and 37 are each provided with a square socket 38 and 39 respectively. 40 is a crank provided with a square block 41 adapted to be fitted into the square socket 38 or 39.

42 is a supporting frame adapted to reinforce the outer edge of the awning 10 and which frame is provided with supporting legs 43, the ends of which are hingedly connected to brackets 44, supported from the face 6 of the building. The casing 5 is provided with notches 45 into which the supporting frame 42 will enter when the awning is being rolled to encased position.

Referring to Fig. 4, we disclose a means whereby the gable portions 10a of the awning 10 may be folded in, flat against the awning 10, when it is desirous of rolling the awning into the casing 5. The free points of the gable portions 10a are provided with rings 46 while the awning 10 is provided with rings 47. 48 is a cord, the ends of which are trained through the rings 47 and connected to the rings 46. Upon pulling the central portion 30 of the cord 48, the gable portions 10a will be drawn into flat position against the under face of the awning 10 and the cord 48 may then be suitably tied to the frame 42 as disclosed in Fig. 4. This will retain the gable portions 10a in flat contact with the body portion of the awning 10 and upon rotation of the roller 29, the gable portion 10a will be rolled up with the body portion of the awning 10.

When desirous of lowering the awning, the operator will insert the squared portion 41 of the crank 40 into the socket 38 and turn the crank in the desired direction. The turning of the crank will cause rotation of the rod 14, through the medium of the worm pinion 22, worm gear 21, pin 25, shaft 23 and the universal connecting link 28. Upon rotation of the rod 14 in the desired direction, the lever arms 15 and connecting links 17, 55 the hinged portion 9 will be swung upwardly to open position as shown in Fig. 2. The operator will then withdraw the squared portion 41 of the crank 40 out of the socket 38 and insert the same into the socket 37. The 60 turning of the crank 40 will cause rotation of the roller 29 through the medium of the worm pinion 39, worm gear 31, shaft 34, collar 35, bevel gear 36 and bevel gear 30, which rotation will allow the awning 10 to unroll from the roller 29. After the awning 10 has

been lowered to the desired position, the crank 40 may be withdrawn and by means of the meshing of the worm pinion 39 with the worm gear 31 the respective parts will be held against further rotation. The operator 70 may now lower the closure member 9 from the position 9a to the position 9b (Fig. 2) which will substantially close the casing and eliminate rain, sleet, snow, dust and the like from gaining entrance to the casing 5.

When it is desired to lower the gable portions 10a, the cord 48 will be untied from the frame 42 and the gable portions 10a of the awning 10 allowed to drop perpendicular. The rings 46 may then be engaged over the 80 hooks 49 extending from the face 6 of the building as shown in Fig. 2.

The foregoing specification and annexed drawings disclose the preferred embodiment of our invention, but it is to be understood that minor changes may be resorted to in the commercial adaptation of our invention without departing from the scope of the invention as hereinafter claimed.

What we claim as new is:

In combination with an awning, a casing; a hinged closure member carried on said casing; a roller, in said casing, upon which an awning is adapted to be rolled; a gear housing; a pinion rotatably mounted in said housing; a tubular shaft; a gear wheel, fixedly carried on one end of said shaft in mesh with said pinion; a pinion rotatably mounted in said housing; a shaft rotatably mounted in said tubular shaft; a gear wheel, fixedly carried on one end of said second mentioned shaft, in mesh with said second mentioned pinion; interconnecting means, between the upper end of said second mentioned shaft and said closure member, for transmitting movement to open and close said closure member; intermeshing gears carried by the opposite end of said tubular shaft and one end of said roller and means for rotating said pinions.

In testimony whereof, we affix our signatures.

GLENWOOD E. NELSON.
ALBERT EDGAR BARKER.
